(57) **CLAIM**

The ornamental design for an electric vehicle charger canopy, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front perspective view of the electric vehicle charger canopy;

FIG. 2 is a front view of the electric vehicle charger canopy of FIG. 1;

FIG. 3 is a rear view of the electric vehicle charger canopy of FIG. 1;

FIG. 4 is a right side view of the electric vehicle charger canopy of FIG. 1;

FIG. 5 is a left side view of the electric vehicle charger canopy of FIG. 1;

FIG. 6 is a top view of the electric vehicle charger canopy of FIG. 1;

FIG. 7 is a bottom view of the electric vehicle charger canopy of FIG. 1;

FIG. 8 is a rear perspective view of the electric vehicle charger canopy of FIG. 1; and,

FIG. 9 is a front perspective view of the electric vehicle charger canopy of FIG. 1 in an environment of use.

The broken lines in the figures show portions of the electric vehicle charger canopy that form no part of the claimed design. The additional broken lines in FIG. 9 illustrate the environment of use and form no part of the claimed design.
